UNITED STATES PATENT OFFICE.

JAY BRIGGS, OF HOOPESTON, ILLINOIS, ASSIGNOR OF ONE-HALF TO WALTER T. GUNN,
OF HOOPESTON, ILLINOIS.

AUTOMATIC RAILWAY-GATE.

1,194,594.

Specification of Letters Patent. Patented Aug. 15, 1916.

Application filed October 18, 1915. Serial No. 56,358.

To all whom it may concern:

Be it known that I, JAY BRIGGS, a citizen of the United States, residing at Hoopeston, in the county of Vermilion and State of Illinois, have invented certain new and useful Improvements in Automatic Railway-Gates, of which the following is a specification.

Prior to my invention, the ordinary practice with relation to railway gates has been to provide a pair of arms, one upon each side of the track or series of tracks, the pair being so connected together that they may be raised and lowered from a single point by an operator or a switchman by means of a crank and intermediate gearing. In other forms of apparatus two pairs of arms are provided mounted respectively on opposite sides of the crossing to be protected and projecting when lowered toward each other and substantially meeting in the center of the crossing. The objections to hand-operated gates are many and obvious and numerous attempts have been made to devise an automatic system for operating the gates controlled by the approach of a train. For this purpose electrical means have been proposed, the circuit of which is closed as the train reaches a predetermined point in advance of the crossing and gates, to lower the gates as or before the train reaches the crossing, and the connections of which are so changed as to raise or open the gates when the train is passing or has passed the crossing. The objections to the systems heretofore proposed have been either that they were not adapted to take care of the many varied situations which arise in connection with railroad crossings of this character, or that they are too complicated for practical use or both. It is necessary not only that the gates shall lower when the train approaches upon the track in the usual direction of traffic and rise when the train passes, but that it shall rise in case the train backs out on the entering end. It is also necessary that the gate be lowered if the train enters in a direction opposite to that of normal traffic and rise as the train leaves either in the direction opposite to the normal, or in the usual direction. Another situation which must be taken care of is when a train approaches the crossing and the engine uncouples from the cars before the crossing

is reached and proceeds without the cars or with less than all of them. In this event the gate should fall as much at the approach of the train and should rise after the engine has passed notwithstanding that the cars still remain within the distance which cars on the track normally operate the gate down, and should again close or go down as the engine again returns to couple on to the train. The problem of operating gates electrically to fulfil these and other conditions is further complicated by the fact that the rails, which must be used in part to control the operation of the electrical devices which operate the gates, generally form part of a block signal system in which the current is normally maintained in the rails and connected apparatus, but is shunted from the signal apparatus by the train when it enters the section. It is obvious that in order to maintain the signal system in dependable condition no electric tension must be put across the rails which would either injure the signaling apparatus or cause the signal devices to go to safety when the train is in the section, and it is also essential that the signal current shall not be short-circuited except when a train is in the section. The requirement of these various situations above enumerated under the conditions described, complicate the problem of an automatic gate to a great extent and the difficulty is further enhanced by the necessity of providing for two and often for three pairs of rails or tracks.

In the system which forms the subject-matter of the present application, all these different conditions and contingencies are taken care of in a comparatively simple manner and with a minimum amount of apparatus and wiring.

The novelty of my improved system consists mainly in the system of wiring as will presently appear.

In the following specification I have described the invention as applied to a single crossing, but it will be understood that a similar system and apparatus may be installed at each crossing desired. Where there is but a single pair of rails at a crossing, a single pair of arms is preferably provided located respectively on opposite sides of the track and connected to the same operating motor, which is located in a suitable housing at one side of the tracks. The arm

upon the same side as the motor is geared thereto and the arm upon the opposite side is connected by a suitable shaft crossing beneath the tracks and gearing. The motor is of a reversing type, either shunt, series, or a combination shunt or series wound, the field being constant and the direction of the current through the armature reversed in order to change the direction of rotation, and so alternately raise and lower the gate. Motors of this character are common and well known, and are provided with pole changing switches to reverse the current through the armature. In my improved construction the pole changing switch is preferably operated from the gate which reverses the connections of the switch at each operation of the gate. A suitable form of pole changing switch is illustrated in the drawings accompanying this specification and described in the latter. In order to operate the gate down the required period before the train reaches the crossing at suitable distances on opposite sides of the latter a section of one of the rails is insulated and by-passed by a connection to maintain the signaling system uninterrupted, and connections are made across the track including the insulated rail for completing the circuit to the pole changing switch and the motor for lowering the gates when a train is upon the insulated section. Preferably a pilot relay operated by a local low voltage battery circuit is employed to control the access of current to the pole changing switch terminals for operating the gate down. Directly at the crossing another rail section is insulated and by-passed for the signaling system and connections formed across the track such that when completed by the passage of a train the motor is operated to raise the gate.

In the accompanying drawings I have illustrated and in the following specification described my preferred form of railway gate apparatus, and system of wiring for operating the same. It is to be understood, however, that the specific disclosure is for the purpose of exemplification only and that the scope of the invention is defined in the following claims, in which I have endeavored to distinguish it from the prior art so far as known to me without, however, relinquishing or abandoning any portion or feature thereof.

Referring now to the drawing, Figure 1 is a side elevation partly in section of a railway gate such as is employed in connection with my invention applied to a railway crossing; Fig. 2 a vertical section on the line 2--2 of Fig. 1; Fig. 3 a face view of the pole changing switch employed in connection therewith; Fig. 4 an elevation at right angles thereto; and Fig. 5 a diagram showing the connections of the pole chang-

ing switch, motor, wiring, circuits, etc. of my system.

The same reference character is applied to each part wherever it is shown in the several views.

Referring now more particularly to the mechanical construction of the gate and operating means as shown in Figs. 1 and 2, it will be noted that it is in the main substantially similar to that of the railway gate shown in my Patent No. 1,134,584, granted to me April 6, 1915, but in view of a number of minor changes over the disclosure of the patent, I will briefly describe the construction before passing to the features with which my invention is more immediately concerned.

Three pairs of rails, *a*, *b*, *c*, are indicated in the drawing and two pairs of arms or gates *d* and *d'*, and *e* and *e'*, which pairs of arms in the construction shown are respectively operated by independent motors, one of which is inclosed in each casing *f* and *f'* and controlled by an entirely distinct and separate system of wiring, switches, etc., from that which operates the other. One system of wiring is controlled by the passage of trains upon one of the outside tracks, as for example, track *a* and the other independent system is controlled by the passage of trains upon track *c*, and track *b* is so connected to one of the wiring systems, as for example, that pertaining to track *c*, that the arms controlled by the latter track are also controlled by track *b*.

Since the construction of the gate operating mechanism upon opposite sides of the trackway is identical, but one of them has been shown with the casing in section to show the interior thereof and but one will be described, it being understood that the description applies equally to the other. Each housing *f* and *f'* carries one gate of each pair and these two gates are mounted upon stub shafts, which are independently rotatable but are preferably coaxial as shown. The shaft of the gate *e'* carries on its inner end a sprocket 8 which is connected by a chain 9 with a sprocket upon the end of a tubular shaft 10. Said shaft is mounted in bearings 11 in a tubular conduit extending beneath the trackway and carries at its opposite end a second sprocket which is connected by a chain 12 with a sprocket upon the shaft 13 of the arm or gate *e*. Obviously by this construction the gates are raised and lowered together. The gate *d'* is mounted for oscillation upon a shaft 14 which is mounted in suitable bearings 15, 16, within the casing and driven by a suitable electric motor 17.

Any suitable means may be employed for connecting the motor to the shaft of the arm *d'* for oscillating the latter but preferably the shaft of the motor armature 18 is ex-

tended and formed with a worm which meshes with a worm gear 19 upon a shaft 20 arranged at right angles to the motor armature shaft and carrying a small spur gear 21 which meshes with a rack quadrant 22 firmly secured to the shaft of the arm d' . It will thus be seen that when the motor is rotated, through the medium of the worm, worm wheel, gear and quadrant rack described, the arm d' is oscillated. Upon the inner end of the shaft 14 of arm d' is mounted a sprocket wheel which is connected by sprocket chain 23 with a sprocket upon the end of shaft 24 which is journaled in and extends through the hollow shaft 10 referred to heretofore and bears upon its other end a sprocket which receives sprocket chain 25. The latter engages a sprocket upon the shaft 26 of arm d corresponding in every respect to the sprocket upon the shaft of arm e' . Thus the arms d and d' are operated up and down in unison and the arms e and e' are similarly operated up and down in unison by mechanism identical in every respect with that described.

Below the operating mechanism are preferably stored the batteries 27, 28 which may be of any suitable type, either storage or primary adapted to furnish the necessary current and voltage. Each casing also contains the pole changing switch by which the direction of the current through the armature is reversed. This switch is so constructed and located with reference to the quadrant upon the shaft of the gate as to be thrown thereby to its opposite position, but for convenience this construction will be described later after the functions and connections of the pole changing switch have been described.

Referring now to Fig. 5 showing in diagram the preferred wiring and connections of the motor and switch, the armature of the motor is indicated at 50, and the field winding at 51, the latter being in shunt to the former as will presently appear. The pole changing switch is indicated in diagram at 52, as comprising two sets of three stationary contacts each, and a reciprocable member having two sets of three contacts each adapted to engage the respective sets of stationary contacts according to the position of said member. One terminal of the battery 103 for operating the motor is connected through certain relays and wiring, to be presently described, when the gate is to be lowered to stationary contact 53, and when the gate is to be raised by other relays and wiring to stationary contact 54, each of these contacts being at the proper time and alternately to the same side of the battery. The other terminal of the battery for operating the motor is permanently connected through the lead 55 to movable contact member 56 of the pole changing switch at 56^a,

and also by a branch connection 57 to the field winding 51 of the motor. The other terminal of the field winding is connected by wire 58 to the quadruple contact element 59 of the movable member of the switch. The upper contacts 60, 61 of the element 59 are adapted to form connection with the source of current by contact with the stationary contacts 53 and 54 respectively, and the lower branch contacts 62, 63, of the quadruple contact element coöperate with the stationary contacts 64, 65 respectively, for the purpose of changing the direction of the current through the armature. The double contact element 59^a engages at its ends 66 and 67, the stationary contacts 68 and 69 respectively, contact 68 being connected to contact 65 referred to above by wire 73 and contact 69 to contact 64 by wire 70. Contacts 65 and 69 are connected to the respective ends of the armature circuit by wires 71 and 72. Contact elements 56 and 59 move in unison but are insulated from each other.

It will now be clear that when the movable member of the pole changing switch is in the position shown in the diagram, and contact 53 is connected to the battery, the course of the current to the armature is from contact 53 through contact 60, element 59, and contacts 62, 64, through wire 70 to contact 69 through wire 71 to armature 50, thence by wire 72 to contact 65, thence by wire 73 to contact 68, contact element 56, wire 74 and lead 55 to battery. When the pole changing switch is in the opposite position, to the right in the diagram, and contact 54 connected to battery, the course of the current through the armature is from contact 54 through contact 61, element 59 and contact 63, to contact 65, thence by wire 72 to the armature, thence by wire 71 to contact 69, thence by contact 67 and element 56 to wire 74 and lead 55 to battery. As heretofore stated the connection through the lead 55 to the battery is constant but the connection from the other terminal to the battery is made at 53 or 54 by a system of relays and wiring to be later described, according as conditions demand the lowering or raising of the gate. As the pole changing switch is correspondingly located by the previous movement of the gate the operation of the latter immediately follows.

Before proceeding with the description of the system by which current is led to the set of contacts of the pole changing switch for lowering and raising the gate respectively, I shall first describe the preferred mechanical construction of the pole changing switch and the means by which it is operated.

Referring now to Figs. 3 and 4, a suitable plate backing or support of insulating material is shown at 75 on which are secured by screws 76, rectangular blocks of insulating material 77, suitably spaced apart for a pur-

pose which will appear. Upon each of these blocks is mounted a set of the contact terminals 53, 64, 68, and 54, 65 and 69 respectively, which have heretofore been described 5 with respect to the diagram. The actual construction of these contacts as shown in Figs. 3 and 4 is as follows: A metal casting 78 is formed with a socket 79 and a flange 80 formed with openings for screwing the 10 casting to the block and insulating material above described. The upper and lower castings are similar to each other and screw to the upper and lower faces of the insulating block respectively, and the intermediate 15 casting is secured to the outer face of the insulating block as at 81. Carbon contacts 82 are received into the sockets 79 of the castings and yieldingly maintained in their outer position by springs 83. Transverse 20 rods 84 are tightly secured in the carbon contacts and extend through slots 85 in the wall of the sockets and serve both to limit the movement of the contacts and as convenient means for attaching the coiled wires 86 25 by which connection is made from the carbon contacts to the terminal connecting screw 87 by which also the leads to the several contacts are secured. Both sets of contacts are identical in the respects described.

30 As heretofore stated the sets of contacts are secured at suitable distances apart and each insulating block is perforated at 88, 89, the pairs of perforations registering with each other for the purpose of receiving and 35 guiding rods 90, 91, on which the movable element of the switch is mounted. The movable member likewise carries two sets of three contacts each adapted to engage respectively the contacts of the stationary sets.

40 It comprises a casting 59 in which are formed two pairs of oppositely facing sockets receiving respectively the carbon contact point 60, 62, 61 and 63, so that these four contacts are all in electrical connection. The 45 contacts 66, 67, are mounted in a separate metal casting 56, which is insulated from but attached to the casting 59 in any suitable manner. The wire 58 is attached to casting 59 by screw 92, and wire 74 to casting 56 50 by screw 93. The operation and connections of the contacts have been described and shown in connection with the diagram and the wiring is omitted from Fig. 3 for the sake of clearness. Means are provided to 55 be presently described, to positively shift the movable member into engagement with the respective stationary sets of contacts and in order to avoid accidental displacement of the movable member, the upper rod 91 upon 60 which it is mounted, is notched at each end as at 91^a to receive the edges of springs 91^b which resist and prevent accidental movement of the rods and movable member, but yield to the intentional operation of the device. In order to shift the movable member

of the pole changing switch from one set of contacts to the other, an arm 94 is pivoted to the supporting plate at 95 and extends loosely between the bolts in the movable member whereby the swing of the arm 70 throws the movable switch member into one position or the other, according to the direction of the movement of the arm.

In order to move the arm suitable mechanical connection is made with the pivoted 75 arm or gate so that the downward movement of the latter throws the arm and the movable member of the switch to the right, in which position the current is delivered to the armature in such a sense or direction as 80 to revolve the same to raise the gate, and the upward swing of the gate moves the switch in the opposite direction to supply the armature of the motor with current in such a direction as to cause the gate to be 85 fed downward.

The preferred construction for operating the switch is as follows: A pair of rods 96, 97, is mounted in brackets 98, 99, on the backing and adapted to reciprocate freely 90 therethrough. Intermediate the ends of the rods a block 99 is secured thereto and is connected by the spring 100 with the arms 94 above described. When the bars 96, 97, and the block 99 carried thereby are reciprocated 95 from one side to the other of the pivotal point of the arm 94, after the spring has passed such point, it serves to throw the arm to its extreme position in that direction, or until stopped by the brackets 98, 99. In 100 addition to the block heretofore described, the rods carry at their opposite ends stops or abutments 101 adjustably secured thereto, which are adapted to be engaged respectively by a stud 102 upon the sector of the pivoted 105 gate or arm as the latter approaches its extreme positions. It will now be seen that when the gate is lowered the stud on the sector engages the stop 101 to the right in the figure, and drives the block 99 to the 110 right, thereby similarly throwing the arm 94 and switch, and when the gate is raised the opposite stop 101 is engaged by the stud and the slide 99 is thrown to the left carrying the arm 94 and the switch in the same 115 direction. Thus when the gate completes its upward movement it shifts the pole changing switch to the "down" position in which it is adapted to supply the motor with current to lower the gate and when it completes its downward movement it shifts the 120 switch to the "up" position.

It will be understood that even when the pole changing switch is in position to supply current to either raise or lower the gate, 125 the action does not take place unless and until the proper circuits have been completed or closed at other points of the system dependent upon the movement of traffic upon the rails.

The connections for completing the respective circuits through the pole changing switch and motor will now be described in connection with the diagram shown in Fig. 5. Said diagram shows two outside tracks, *a*, *c* and an intermediate track *b*, the outside tracks being respectively intended for traffic going in opposite directions and the center track being a passing track for clearing the outside tracks. While I have shown the three tracks I have indicated only the wiring and apparatus for controlling the gates with respect to one of the outside tracks and the central or passing track. It will be understood, however, that an identical arrangement is employed with respect to the other outside track for operating the other pair of gates but without connections for the central track.

In addition to the gate operating mechanism and in connection therewith I have shown and will describe wiring for operating a bell to indicate the approach of a train to the crossing though there is nothing new in the bell system *per se* but only in conjunction with the other features of the system. The crossing is indicated by the broken lines *A*, *A*. It is of course necessary that the gate be lowered and be in position before a train reaches the crossing. Therefore I have provided upon each side of the crossing and at such distance therefrom that the gate may be completely lowered a sufficient interval of time before the train reaches the crossing, the terminals of a circuit which is completed by the passage of a train and energizes a relay, which in turn energizes a second relay controlling the transmission of electricity to that set of stationary contacts of the pole changer, which are identified with the downward movement of the gate. I provide at the crossing the contacts of another circuit adapted to be closed by the passing of a train, which circuit contains a relay for completing a circuit through the "up" side of the pole changing switch, *i. e.*, that side which supplies the current to the motor in such a sense as to rotate the latter and raise the gate.

Connection is made from one terminal of the power battery 103 to the pole changing switch and the field winding of the motor by the lead 55, as stated above. The connection from the other terminal of the battery to the switch is controlled jointly by relays 104, 105 and 106. Each of these relays controls an armature having a series of switches or movable members connected thereto which are indicated diagrammatically in the drawing simply as pivoted bars 107, 108, etc., controlling various circuits. Relay 104 is energized when a train approaches from the left as shown in the drawing or in the normal direction of the traffic and relay 105 is energized when a train ap-

proaches from the right or against the normal direction of traffic, and each of these relays when energized closes the circuit to the "down" side of the pole changing switch. Relay 106 however, is energized whenever a train reaches the crossing from either direction and closes the circuit to raise the gate. All this will be better understood in connection with the detailed description of the apparatus and connections.

In order to install my automatic gate operating system without interfering with the signal system, at each point of control I insulate a section 109, 110 and 111 from one of the rails and connect said section to the opposite rail in a circuit comprising a relay 112, 106, (referred to above) and 113, and low voltage batteries 114, 115 and 116. The relay 112 is energized when a train enters upon section 109 and completes the circuit and its armature 117 is attracted to close a circuit comprising continuous line wire 118, wire 119, battery 120, wire 120^a, the main winding of relay 104, wire 121 and section wire 122. The completion of this circuit by the armature 117 of relay 112 therefore energizes relay 104, causing it to attract its armature and raise the switches controlled thereby, to their upper contacts. One of these switches, to wit, switch 123, closes the circuit from the battery 103 through wire 124, said switch, wires 125, 126, switch 127 and wire 128 to the "down side" of the pole changing switch at 53. We have seen that whenever the gate rises it operates the movable member of the pole changing switch into engagement with the "down side" of said switch, so that when the circuit from the battery to said "down side" of the switch is closed as just described, the current finds a down path to the armature to revolve the same in a direction to lower the gate.

Were no provision made for maintaining the power circuit closed as just described, as soon as the train passed off the rail section 109 deenergizing the relay 112, the circuit of relay 104 would open and permit the switch 123 to open the down circuit, perhaps before the gate was completely lowered. I therefore provide means for maintaining a sufficient current through the relay 104 to maintain its armature up until the train passes the crossing, but insufficient to raise the armature from its lower position. For this purpose I provide a secondary winding on the relay 104 which together with battery 115 is connected across the rails adjacent the crossing by wires 129, 130, 131, 132, 132^a and 158. The armature being in its attracted position is maintained there by the relatively feeble current of battery 115 which is of such low voltage as not to interfere with the signaling system. This circuit it will be noted is closed by a train at any point on the track with which it is connect-

ed, but the strength of current is diminished with the recession of the train from the crossing until it becomes too feeble to maintain the armature. The voltage resistance, etc., are so related however that the armature is held until the train passes beyond the insulated section 109 or 111 as the case may be.

It is to be remembered that with the downward movement of the gate the movable member of the pole changing switch is shifted into contact with the stationary contacts identified with the "up" movement of the gate; but the "up" circuit is open at relay 106 until the train reaches the crossing, and consequently the gate remains down. When the crossing is reached the relay 106 is energized, attracting its armature and operating the switch 127 to break the "down" circuit and the switch 133 to complete the "up" circuit. The current for energizing relay 106 is derived from battery 115 and flows through wires 132, 132^a and 158 to the undivided track, thence through the train to insulated rail section 110, thence by wire 134, switch 135 and wire 136, to relay 106, and thence by wires 137 and 131 to battery 115. As heretofore stated the energization of relay 106 breaks the "down" circuit at 127 and also completes the "up" circuit at 133. The power current then flows from battery 103 through wires 138 and 138^a, switch 133, wires 139 and 140 to the "up" side of the pole changing switch at 54. The latter having been previously closed upon the "up" side by the shifting of the movable member by the gate as the latter was lowered, the motor is now operated in the reverse direction and raises the gate, which in its upward movement again shifts the movable element of the pole changing switch back to the "down" position. No downward movement of the gate results at this time however notwithstanding that the armature of 104 is still up for the reason that the "down" circuit is held open at switch 127 by the relay 106. As soon as the train has passed completely off the insulated section 110, the above described energizing circuit of relay 106 is of course broken, which would permit the armature of said relay and the switches 133 and 127 to fall away, thereby opening the "up" circuit at switch 133 perhaps before the gate is entirely raised and closing the "down" circuit at switch 127, were it not for the fact that relay 106 is still energized by the battery 115 through a second circuit which is as follows: From battery 115, through wires 132, 169, switch 107 which is still maintained in its upper position by the relay 104 as above pointed out, wires 170, 171, switch 172, wires 173, 174, 175, switch 176, wire 136, relay 106, and wire 137 to battery. Thus the relay 106 is energized and its switch maintained in the raised position until the circuit just described is broken by the release of switch 107 by re-

lay 104. As a consequence the "up" circuit is maintained closed and consequently the "down" circuit open until the train has passed beyond the point where it influences the relay 104, when said relay and relay 106 are deenergized and the parts restored to their original position. As heretofore stated the track is provided beyond the crossing, that is to say, upon the leaving side thereof, with another insulated rail section 111, pilot relay 113, battery 116 and circuit to be closed by the passage of a train, similar to the installation upon the approaching side of the crossing for closing a somewhat similar circuit by means of the switch 142 through relay 105 somewhat similar in its connections and functions to relay 104. At the time, however, that the train receding from the crossing passes insulated rail section 111, the "down" circuit is still maintained open at 127 by the relay 106 so that the energization of relay 105 effects no operation of the gate. When, however, for any reason a train approaches the crossing against the normal direction of traffic as it reaches the rail section 111 it operates relay 113, and a circuit is closed through the switch 142 of said relay, from battery 120, through wires 119, 118 and 144, said switch wire 146, section wire 147, wire 148, the main winding of relay 105, wires 149, 120^a to battery 120. Relay 105 which is similar to relay 104 now attracts its armature, raising the switches controlled thereby including switch 227, thereby completing a circuit from the power battery 103, through wires 138 and 152, switch 227, wire 153, wire 126, switch 127, wire 128, to the down side of the pole changing switch. The gate is then operated down reversing the pole changing switch. When the train reaches the crossing the relay 106 does not act as when the train is moving in the direction of normal traffic because the armature of the relay 105 has raised switch 135, and it is now maintained in the upper position, or caused to stick by the passage of a feeble current through a secondary winding of said relay, and hence the circuit through the relay 106 is broken at 135.

The circuit through the secondary coil of relay 105 is derived from battery 115 through the following path: Wires 131, 130 and 154, the secondary coil of relay 105, wire 155, track section 156, the train running gear, track 157 and wires 158, 132^a and 132. Thus the energization of relay 106 is prevented during the passage of the train over the insulating rail section 110 at the crossing, and the gate remains down until the train passes out at the normal entering end. With the lowering of the gate the pole changing switch has in the meantime changed as usual to the "up" position. As the train passes out beyond the point where it affects said secondary circuit, the resist-

ance of the circuit through the secondary of the relay 105 increases to such an extent that the latter drops its armature thus opening the "down" circuit at switch 227. At 5 the same time the dropping of switch 160 closes an "up" circuit through the motor as follows: From battery 103, through wire 124, switch 123, wire 161, switch 160, wire 162, wire 140, through the pole changing 10 switch and motor and back to battery through the common connection 55. The pole changing switch in the meantime having been shifted to the "up" position by the action of the gate, the latter is now 15 raised, shifting the pole changing switch to the "down" position and so breaking the circuit. The system is thus restored to its original condition ready to lower the gates before the passage of the next train.

20 In case a train enters the field of the gate operating system coming in the normal direction of traffic inside or beyond the insulated track section 109, but fails to pass the crossing and backs out over the entering 25 end, the following takes place: The relay 104 is energized by the connections described above and the pole changing switch being in the "down" position the gate is lowered. The relay 104 having attracted its armature, 30 the latter will stick or be maintained in closed position as long as the train is near enough to maintain the current in the circuit of the secondary winding of relay 104 previously described and comprising bat- 35 tery 115, wires 132, 158, continuous rail 157, sectional rail 156, wire 129, the secondary winding of relay 104, wires 130 and 131. Thus the "down" circuit remains closed as long as the train is between the insulated 40 rail section 109 and the crossing, except as it is broken by the descent of the gate which shifts the pole changing switch to the "up" position. When the train backs out, however, the resistance of the secondary cir- 45 cuit of relay 104 is so increased that it ultimately drops its armature and switches controlled thereby including switch 123, thereby breaking the "down" circuit at this switch. This closes a circuit through the 50 pole changing switch in the "up" position and the motor as follows: From battery 103, through wire 124, switch 123, wire 161, switch 160, wire 162 to the pole changing switch and motor and hence back by the 55 common connection 55 to battery, or in other words, through the same connections by which the arm is raised when a train enters in a direction opposite to that of normal traffic and passes out of the normal entering 60 end. The gate restores the pole changing switch to "down" position and the system is restored to normal condition.

If the train enters from the direction opposite that of normal traffic but does not 65 pass the crossing and backs out, the fol-

lowing takes place: The connections for lowering the gate are made precisely as if the train passed completely through the field of the gate operating system, relay 105 being energized and closing a "down" circuit through the switch 227. The circuit through the secondary winding of relay 105 heretofore described maintains the armature and switches identified with said relay in the upper position as long as the train is 75 sufficiently near as before described. When, however, the train backs out in the normal direction of traffic, the current through the secondary coil is enfeebled until the relay drops its armature and the associated switches. The "up" circuit heretofore described as formed when none of the relays is energized is thus completed from the battery 103 through wire 124, switch 123, wire 124, switch 160, wire 162, wire 140, to the pole changing switch and motor and back to battery. Thus the gate is operated up 85 and the parts restored to normal position.

Whenever a train enters the track in the normal direction of traffic and the engine cuts off from the main part of the train leaving the latter standing on the insulated rail section 109, or between the same and the crossing, and proceeds past the crossing, the operation is as follows: The gate is lowered 90 and maintained in lowered position as usual when the train enters the field of the gate operating system until the engine, having cut off from the cars, reaches the insulated rail of the crossing. Then, the pole changing switch having been shifted to the "up" 95 position as usual, the engine closing the circuit heretofore described, through relay 106, raises the gate. The pole changing switch is thus shifted to the "down" position but the gate is not operated "down" at this time even though the switches controlled by the relay 104 are maintained in the upper or attracted position because of the presence of the cars which maintains a current in the 100 secondary winding thereof. This is true because the relay 106 energized by the battery 115 and the second circuit heretofore described by reason of the presence of the cars maintains the down circuit open at the 105 switch 127. If the engine now returns and couples on to the rear end of the train and takes the train out of the field of the gate operating system, the following takes place: As the engine passes the insulated track 110 section 111, relay 113 and consequently relay 105 are energized as above described. This closes the previously described "down" operating circuit from battery 103 through wires 138 and 152, switch 227, wires 153 and 126, switch 127, wire 128, to the pole changing switch, which is then in the "down" position and the motor so that the gate is again closed or lowered. The previously described 115 circuit through the secondary winding of the 120 125 130

relay 105, maintains the armature of the latter in a raised position so long as the train is within the field of the gate operating system. Therefore, when the engine reaches the 5 insulated section at the crossing, relay 106, the circuit of which is maintained open at switch 135 by relay 105, is not energized and therefore the gate is not raised until the engine has again coupled onto the train and 10 the train passed beyond the insulated section 111, at which time the relays are all deenergized, and an "up" circuit is formed from battery 103, through wire 124, switch 123, wire 161, switch 160, wire 162, wire 140 to 15 the pole changing switch and motor. The gate is thereby raised, again shifting the pole changing switch to the "down" position, so that the parts are all in normal position.

20 The above description relates only to a single track and the connections for operating the crossing gate properly with relation to the traffic thereon. As heretofore stated, the identical arrangement including a second pair of gate arms may be duplicated with reference to the second track, the arms of both gates being located outside both tracks as is common. Where a third or passing track is employed the requirements are 25 somewhat different from those which obtain in connection with the main tracks because there is no signal system interference with which must be guarded against. For this passing track therefore the pilot relays are 30 operated on a normally closed circuit. Low voltage batteries 263, 264 are connected across the rails of the passing track, a suitable distance from the crossing at opposite sides thereof, and the rails electrically 35 divided and insulated substantially at the crossing as at 181 and 182. A pair of interlocking relays 267 of well known construction are provided which are connected across the rails respectively upon opposite sides of 40 the point of insulation by wires 269, 270, 271, 272, so that each relay completes the circuit of the battery which is located on the same side of the insulation therewith and is normally energized thereby. The armatures of 45 these relays control a circuit through the primary winding of the relay 104. The switches 273, 274, 275, 276 are normally maintained in their upper position by the magnets of the relays. When, however, a 50 train sufficiently closely approaches the connections of battery 263 it short circuits the corresponding relay 267 which permits its armature to drop. Thus a circuit is thereby closed including the battery 120, wires 177, 55 178, switches 276, 274, wires 179, 180 and 121, relay 104, wire 120^a to battery.

60 The energization of relay 104 operates as heretofore described to close a circuit from battery 103 through the switches 123, etc., to 65 the "down side" of the pole changing

switch so that the gate is lowered. At the same time relay 267 locks out relay 268 so that when the latter is deenergized by the train passing beyond the insulated points 181, 182 at the crossing, the switches controlled thereby drop to an intermediate position only and not to the lower position whereby contact would be made at 183. Therefore when the train on this passing track passes beyond the point at which it 70 materially short-circuits battery 264, the relay 267 being again energized opens the circuit through the relay 104, thus deenergizing the latter which thereupon drops its armature and switches controlled thereby, 75 thus closing the "up" circuit as previously described, and the gate in the meantime having shifted the pole changing switch to the "up" position the gate is again raised. In like manner if a train approaches on the 80 passing track from the other direction the relay 268 is first deenergized and locks out relay 267, dropping the switches 275, 276 and thus closing a circuit including battery 120, wires 177, 184, switches 275, 273, wires 90 186, 180, 121, relay 104, wire 120^a to battery. Relay 104 being thus energized attracts its armature closing the "down" circuit as heretofore described so that the gate is operated down. Because of the comparative 95 simplicity of the problem by reason of the fact that there is no signaling system upon this intermediate or passing track and because of the rare movement of trains upon this track, the above system is sufficient to 100 provide for the proper operation of the gate with relation to any traffic upon this track.

105 In connection with the above described automatic gate operating means I employ a warning signal at the crossing which indicates the approach of a train before it reaches the latter point. A bell 187 is located adjacent the crossing and connected for operation by the battery 120 through a circuit comprising wires 120^a, 189 normally 110 open switch 190, wire 191, the magnetic coil of the bell, wire 192 and wire 119. Switch 190 is controlled by the relay magnet 193 which is included in a circuit comprising battery 120, wires 119, 118, 194, a normally 115 open switch 195, wires 196, 197, 198, the winding of said magnetic relay, wires 199, 189 and 120^a and said battery 120. Relay 195 is controlled from the track with which it is identified in the usual manner by a battery 120 and electro magnetic device in a normally closed circuit. It will be obvious that when the switch 195 is closed by the entry of a train on the track with which it is identified the switch 190 is closed by relay 193 thus ringing the bell at the crossing.

120 It will be understood that many changes may be made in the construction and connections of the gate and its operating means without departing from my invention. 130

Thus, for example, for the swinging gate specifically shown, a reciprocating gate either raised and lowered or moved horizontally might be substituted; the circuits for initiating the operation of the device might be closed directly by the train without the interposition of the pilot relays; other forms of reversing motor than that described might be used, *e. g.*, the field current might be reversed instead of the armature current, the armature and field might be in series instead of in multiple, *et cetera*; in its broader aspect the invention is independent of the particular form of means employed for the reversing of the motor and the described circuits for supplying the current to the pole changing switch and motor; many other changes will suggest themselves to those skilled in the arts to which this invention relates.

I claim:

1. An automatic gate for railway crossing comprising a gate proper, a motor for operating the gate in opposite directions, a switch for reversing the motor having two sets of stationary contacts and a movable contact member, means for moving said contact member alternately into engagement with the respective stationary sets of contacts, a source of current, a connection from the source of current to one side of said switch comprising a relay energized by a train on the track at some distance from the crossing, and connections from the source of current to the other side of the switch comprising a relay energized by a train on the track substantially at the crossing. 90
2. A gate for railway crossings comprising a gate proper and a reversing motor for opening and closing the same, a source of current, a switch having two sets of stationary contacts and a movable member having contacts to engage the stationary contacts, means to shift the movable member alternately into engagement with the respective sets of contacts, connections from the contacts to the motor and to the source of current such that when the movable member of the switch engages one set of contacts current flows to the motor in a direction to operate the same to close the gate and when the movable member engages the other set of contacts current flows to the motor in a direction to rotate the same in the opposite direction to open the gate, a relay controlling the connections to the first said set of stationary contacts energized by a circuit which is closed by a train on the track at some distance from the crossing, and a second relay controlling the connections to the other said set of stationary contacts energized by a circuit closed by a train on the track adjacent said crossing. 105
3. A gate for railway crossings comprising a gate proper and a reversing motor for opening and closing the same, a source of current, a switch having two sets of stationary contacts and a movable member having contacts to engage the stationary contacts, means to shift the movable member alternately into engagement with the respective sets of contacts, connections from the contacts to the motor and to the source of current such that when the movable member of the switch engages one set of contacts current flows to the motor in a direction to operate the same to close the gate and when the movable member engages the other set of contacts current flows to the motor in a direction to rotate the same in the opposite direction to open the gate, a relay controlling the connections to the first said set of stationary contacts energized by a circuit which is closed by a train on the track at some distance from the crossing, and a second relay controlling the connections to the other said set of stationary contacts energized by a circuit closed by a train on the track adjacent said crossing. 110
4. A railway gate comprising a gate proper and a reversing motor for opening and closing the same, a switch having two operative positions in one of which current is supplied to the motor to operate it in one direction and in the other of which positions current is supplied to the motor to operate it in the other direction, an electric system including relays adapted to be energized by the presence of a train on the track at some distance from the gate proper for closing the same and to be energized by the presence of a train at a nearer point to the gate to open the same. 115
5. An automatic gate for railway crossings comprising a gate proper, a reversible motor for opening and closing the same, a pole changing switch connected to the motor for supplying it with current to operate it in opposite directions, comprising two sets of stationary contacts and a movable member also carrying contacts adapted and arranged when the member is in engagement with one set of contacts to supply current to the motor to drive it in one direction and when the member is in engagement with the other set of contacts to drive the motor in the other direction, said member being shifted with each operation of the gate, a source of current for operating the motor, 120 connections from said source of current to the respective sets of stationary contacts and means controlling said connections operated by the approach of a train for closing the gate and by the nearer approach of a train 125 to the crossing for closing connections to open the gate. 130
6. An automatic gate for railway crossings comprising a gate proper, a reversible motor for opening and closing the gate, a

- source of current for operating said motor, a pole changing switch interposed between said source of current and said motor and adapted when in one position to supply current for operating the motor in one direction and in the other position to supply current for operating the motor in the other direction, the said switch being reversed by the operation of the gate, a relay energized 5 by a train on the track for closing a connection from said source of current to the switch when the latter is in one position to supply current to the motor in one direction and a relay closing a connection to said switch when the latter is in its other position for supplying current to the motor to operate the same in the other direction.
7. An automatic gate for railway crossings comprising a gate proper, a reversible 20 motor for opening and closing the gate, a source of electric energy for said motor, a pole changing switch comprising stationary contacts and a movable member adapted in one position to engage one set of stationary 25 contacts and in another position to engage another set of stationary contacts, one of the contacts of each set being connected to the source of electrical energy, a relay controlling the connections to one of said sets and 30 controlled by a train for supplying current to the motor to operate it in one direction, and a relay controlling the connection to the other said contacts and controlled by a train to supply current to operate the motor in 35 the other direction.
8. An automatic gate for railway crossings comprising a gate proper, a reversible motor for opening and closing the gate, a source of current for operating said motor, 40 a pole changing switch having a pair of stationary contacts connected to the source of current through different paths respectively, and a movable member adapted when in engagement with one of said contacts to 45 supply the current in one direction to the motor and when in engagement with the other contact to supply current in the other direction to said motor, the connection from said source of current to one of said contacts 50 being controlled by a relay controlled by a train on the track, and the connections from the other of said contacts to the source of current being likewise controlled by a relay controlled by a train on the track.
- 55 9. An automatic gate for railway crossings comprising a gate proper, a reversible motor for opening and closing the gate, a source of current for actuating the motor, a pole changing switch having a pair of stationary contacts each connected with the source of current and a movable element adapted to engage said contacts alternately, and adapted and arranged when in engagement with one set of contacts to supply current to the motor for operating the gate 60 down and when in engagement with the other of said contacts to supply a current to the motor for operating the gate up, a relay controlling the connections to the contacts for operating the gate down energized 70 by a train on the track at some distance from the crossing, and a relay controlling the connections of the contacts for operating the gate up controlled by a train at a nearer point to the crossing. 75
10. An automatic gate for railway crossings comprising a gate proper movable in opposite directions with relation to the crossing, a reversible electric motor for moving said gate, a source of electrical energy 80 for supplying said motor, a pole changing switch comprising a pair of stationary contacts, electrical connections from each of said contacts to the same pole of said source of electrical energy, said pole changing switch also comprising a movable member connected to the other pole of the same source of electrical energy and adapted to engage said contacts alternately, means for actuating said movable member in opposite 85 directions, connections from said movable member and stationary contacts to the motor such that when the movable member is in engagement with one contact the motor will receive current to turn it in one direction 90 and when the movable member is in engagement with the other contact the motor will receive electrical energy to turn it in the other direction, a relay controlling the connections from one of said contacts to the 95 source of energy and controlled by a train upon the rails at a distance from the crossing and a relay controlling the connections from the other of said contacts to the source of energy and controlled by a train at the 100 crossing. 105
11. An automatic gate for railway crossings comprising a gate proper movable in opposite directions with relation to the crossing, a reversible electric motor for moving said gate, a source of electrical energy 110 for supplying said motor, a pole changing switch comprising a pair of stationary contacts, electrical connections from each of said contacts to the same pole of said source of electrical energy, said pole-changing switch also comprising a movable member connected to the other pole of the same source of electrical energy and adapted to engage said terminals alternately, means for actuating said movable member in opposite 115 directions, connections from said movable member and stationary contacts to the motor such that when the movable member is in engagement with one set of stationary contacts the motor will receive current to turn it in one direction and when the movable member is in engagement with the other set of contacts the motor will receive electrical energy to turn it in the other direction, the 120 125

connections between one of said contacts and the source of energy being normally open, a relay energized by a train upon the rails at a distance from the crossing to close 5 said connections and a relay controlling the connections from the other of said contacts to the source of energy and operated by a train at the crossing.

12. An automatic gate for railway crossings comprising a gate proper movable in opposite directions with relation to the crossing, a reversible electric motor for moving said gate, a source of electrical energy for supplying said motor, a pole changing 15 switch comprising a pair of stationary contacts, electrical connections from each of said contacts to the same pole of said source of electrical energy, said pole-changing switch also comprising a movable member 20 connected to the other pole of the same source of electrical energy and adapted to engage said terminals alternately, means for actuating said movable member in opposite directions, connections from said movable 25 member and stationary contacts to the motor such that when the movable member is in engagement with one set of stationary contacts the motor will receive current to turn it in one direction and when the movable 30 member is in engagement with the other set of contacts the motor will receive electrical energy to turn it in the other direction, the connections from one of said contacts to the source of energy being normally open, a relay 35 energized by the presence of traffic on the rails at a distance from the crossing to close said connections and a second relay energized by a train at the crossing acting to open said connections.
13. An automatic gate for railway crossings comprising a gate proper movable in opposite directions with relation to the crossing, a reversible electric motor for moving said gate, a source of electrical energy 40 for supplying said motor, a pole changing switch comprising a pair of stationary contacts, electrical connections from each of said contacts to the same pole of said source of electrical energy, said pole changing 45 switch also comprising a movable member connected to the other pole of the same source of electrical energy and adapted to engage said terminals alternately, means for actuating said movable member in opposite 50 directions, connections from said movable member and stationary contacts to the motor such that when the movable member is in engagement with one set of stationary contacts the motor will receive current to turn it in one direction and when the movable 55 member is in engagement with the other set of contacts the motor will receive electrical energy to turn it in the other direction, the connections from one of said contacts to the source of electrical energy being normally 60 open, a relay energized by a train on the rails at a distance from the crossing to close said connections, the connections between the other stationary contact and the source of electrical energy being likewise normally 65 open and a second relay energized by a train at the crossing to close the last mentioned electrical connection and open the first mentioned set.
14. An automatic gate for railway crossings comprising a gate proper movable in opposite directions with relation to the crossing, a reversible electric motor for moving said gate, a source of electrical energy for supplying said motor, a pole changing 70 switch comprising a pair of stationary contacts, electrical connections from each of said contacts to the same pole of said source of electrical energy, said pole-changing switch also comprising a movable member 75 connected to the other pole of the same source of electrical energy and adapted to engage said terminals alternately, means for actuating said movable member in opposite directions, connections from said movable member and stationary contacts to the motor such that when the movable member is in engagement with one set of stationary contacts the motor will receive current to turn it in one direction and when the movable 80 member is in engagement with the other set of contacts the motor will receive electrical energy to turn it in the other direction, one of said connections between the switch and the source of energy including a normally 85 open switch (123), a relay (104), the armature of which is operatively connected to the switch 123, said relay having a main and an auxiliary coil, the circuit of the primary coil being closed by a train on the rails at 90 a distance from the crossing to cause said coil to attract its armature, and the circuit through the auxiliary coil of the relay being closed by a train on the rails at a point nearer the crossing, whereby the relay is 95 energized sufficiently to cause it to maintain its armature in closed position but not to cause it to close the armature.
15. An automatic gate for railway crossings comprising a gate proper movable in opposite directions with relation to the crossing, a reversible electric motor for moving said gate, a source of electrical energy for supplying said motor, a pole changing 100 switch comprising a pair of stationary contacts, both contacts having normally open electrical connections to the same pole of said source of electrical energy, said pole changing switch also comprising a movable member 105 connected to the other pole of the same source of electrical energy and adapted to engage said contacts alternately, means for actuating the movable member, connections from said movable member and stationary contacts to the motor, such that 110
16. An automatic gate for railway crossings comprising a gate proper movable in opposite directions with relation to the crossing, a reversible electric motor for moving said gate, a source of electrical energy for supplying said motor, a pole changing 115 switch comprising a pair of stationary contacts, both contacts having normally open electrical connections to the same pole of said source of electrical energy, said pole changing switch also comprising a movable member 120 connected to the other pole of the same source of electrical energy and adapted to engage said contacts alternately, means for actuating the movable member, connections from said movable member and stationary contacts to the motor, such that 125
17. An automatic gate for railway crossings comprising a gate proper movable in opposite directions with relation to the crossing, a reversible electric motor for moving said gate, a source of electrical energy for supplying said motor, a pole changing 130 switch comprising a pair of stationary contacts, both contacts having normally open electrical connections to the same pole of said source of electrical energy, said pole changing switch also comprising a movable member connected to the other pole of the same source of electrical energy and adapted to engage said contacts alternately, means for actuating the movable member, connections from said movable member and stationary contacts to the motor, such that 135

when the movable member is in engagement with one set of stationary contacts the motor will receive current to turn it in one direction, and when the movable member is in engagement with the other set of stationary contacts the motor will receive electrical energy to turn it in the other direction, an insulated section in one of the rails at a distance from the crossing, an electrical connection between the ends of the rails on opposite sides of said section, a relay energized by a train upon the insulated rail section to close the connections between one of said contacts and the source of electrical energy and a relay energized by a train at the crossing for closing the other said connections.

16. An automatic gate for railway crossings, comprising a gate proper movable in opposite directions with relation to the crossing, a reversible electric motor for moving said gate, a source of electrical energy for supplying said motor, a pole-changing switch comprising a pair of stationary contacts, both contacts having normally open electrical connections to the same pole of said source of electrical energy, said pole-changing switch also comprising a movable member connected to the other pole of the same source of electrical energy and adapted to engage said contacts alternately, means for actuating the movable member, connections from the movable member and stationary contacts to the motor, such that when the movable member is in engagement with one set of stationary contacts the motor will receive current to turn it in one direction, and when the movable member is in engagement with the other set of stationary contacts the motor will receive electrical energy to turn it in the other direction, an insulated section in one of the rails at a distance from the crossing, an electric connection between the ends of the adjacent rails, a relay energized to attract its armature by a train at the insulated section to close one of said connections between the pole changing switch and the source of electrical energy and less strongly energized to maintain its armature in attracted position by a train on rails between the insulated section and the crossing.

17. An automatic gate for railway crossings, comprising a gate proper movable in opposite directions with relation to the crossing, a reversible electric motor for moving said gate, a source of electrical energy for supplying said motor, a pole changing switch comprising a pair of stationary contacts, both contacts having normally open electrical connections to the same side of said source of electrical energy, said pole changing switch also comprising a movable member connected to the other side of the same source of electrical energy and adapted to engage said contacts alternately, means

for actuating the movable member, connections from said movable member and stationary contacts to the motor, such that when the movable member is in engagement with one set of stationary contacts the motor will receive current to turn it in one direction, and when the movable member is in engagement with the other set of stationary contacts the motor will receive electrical energy to turn it in the other direction, an insulated section in one of the rails at a distance from the crossing, a relay the armature of which when attracted closes the connection between one of said contacts and the source of electrical energy, said relay having a main and an auxiliary coil, the main coil when energized being of sufficient strength to attract the armature and being energized by a train on the rails at the insulated section and the auxiliary coil being connected across the uninsulated rail sections and adapted to maintain the armature in closed position when there is a train upon the rails adjacent said crossing and a relay controlling the connections from the other of said contacts to the source of energy and operated by a train at the crossing.

18. An automatic gate for railway crossings, comprising a gate proper movable in opposite directions with relation to the crossing, a reversible electric motor for moving said gate, a source of electrical energy for supplying said motor, a pole changing switch comprising a pair of stationary contacts, having electrical connections to the same side of said source of electrical energy, said pole changing switch also comprising a movable member connected to the other side of the same source of electrical energy and adapted to engage said contacts alternately, means for actuating the movable member, connections from said movable member and stationary contacts to the motor, such that when the movable member is in engagement with one set of stationary contacts the motor will receive current to turn it in one direction, and when the movable member is in engagement with the other set of stationary contacts the motor will receive electrical energy to turn it in the other direction, an insulated section in the rails at a distance from the crossing, an insulated section at the crossing, a relay energized by a train at the first insulated section to close a connection between one of the contacts and the source of electrical energy and a relay energized by a train at the second said insulated section to close the connection between the other contact and the source of electrical energy.

19. An automatic gate for railway crossings, comprising a gate proper movable in opposite directions with relation to the crossing, a reversible electric motor for moving said gate, a source of electrical energy

- for supplying said motor, a pole changing switch comprising a pair of stationary contacts, both contacts having normally open electrical connections to the same side of said source of electrical energy, said pole changing switch also comprising a movable member connected to the other side of the same source of electrical energy and adapted to engage said contacts alternately, means 5 for actuating the movable member, connections from said movable member and stationary contacts to the motor, such that when the movable member is in engagement with one set of stationary contacts the motor 10 will receive current to turn it in one direction, and when the movable member is in engagement with the other set of stationary contacts the motor will receive electrical energy to turn it in the other direction, an 15 insulated section in the rails at a distance from the crossing, an insulated section at the crossing, a relay energized by a train at the first insulated section to close a connection between one of the contacts and the source 20 of electrical energy and a relay energized by a train at the second said insulated section to close the connection between the other contact and the source of electrical energy and more feebly energized by a train adjacent 25 the corresponding relay to maintain its armature in closed position.
20. An automatic gate for railway crossings, comprising a gate proper movable in opposite directions with relation to the 25 crossing, a reversible electric motor for moving said gate, a source of electrical energy for supplying said motor, a pole changing switch comprising a pair of stationary contacts, both contacts having normally open 30 electrical connections to the same side of said source of electrical energy, said pole changing switch also comprising a movable member connected to the other side of the same source of electrical energy and adapted 35 to engage said contacts alternately, means 40 for actuating the movable member, connections from said movable member and stationary contacts to the motor, such that when the movable member is in engagement with 45 one set of stationary contacts the motor will receive current to turn it in one direction, and when the movable member is in engagement with the other set of stationary contacts the motor will receive electrical energy 50 to turn it in the other direction, an insulated section in the rails at the crossing, a relay 55 a coil of which is in circuit with said insulated section and the other rail, and energized by a train at the insulated section 60 to attract its armature, and other connections from the relay across the uninsulated rails and comprising a battery adapted to maintain the armature of the relay in attracted position so long as there is a train 65 adjacent the crossing.

21. An automatic gate for railway crossings, a gate proper, a reversible motor movable in one direction to close the gate and in the other direction to open the gate, a pole changing switch having a movable member 70 and a pair of stationary contacts, connections from one of said contacts to the motor to operate it to open the gate, connections from the other of said contacts to the motor to operate the latter in a direction to close 75 the gate, a source of current, a connection from the source of current to the gate closing contact comprising two switches 123, 127, connections from the source of current to the gate opening contact comprising a 80 switch 133, a relay 104 controlled by a train upon the rails at a distance from the crossing operating when energized to close switch 123 and a relay 106 controlled by a train on the rails at the crossing to close switch 133 85 and open switch 127.

22. An automatic gate for railway crossings, a gate proper, a reversible motor movable in one direction to close the gate and in the other direction to open the gate, a 90 pole changing switch having a movable member and a pair of stationary contacts, connections from one of said contacts to the motor to operate it to open the gate, connections from the other of said contacts to 95 operate the latter in a direction to close the gate, an insulated section 109 in one of the rails at a distance from the crossing, a connection from the opening contact of the pole changing switch to the source of energy 100 comprising a normally open switch 123, a relay 104 the armature of which is connected to said switch and adapted to close the same, said relay having a coil adapted to be energized by a train at the insulated section, 105 and an auxiliary coil connected across the uninsulated rails and adapted when energized after the armature is in closed position to maintain it in such position.

23. In an automatic railway gate and in 110 combination with the gate proper thereof, a reversible motor for raising and lowering the gate, a pole-changing switch for reversing the motor comprising contacts 53 and 54 and a movable member for connecting said 115 contacts respectively with the motor to operate it in opposite directions, a source of current, a connection from contact 53 to said source comprising normally closed switch 127 and normally open switches 123 120 and 227 arranged in parallel and respectively in series with normally closed switch 127, relay 104 adapted to close switch 123, insulated rail section 109, connections between said insulated rail section and relay 125 101 such that a train on said rail section energizes relay 104, relay 105 adapted to close switch 227, insulated rail section 111 and connections therefrom to relay 105 such that a train on said rail section energizes 130

relay 105, relay 106 adapted when energized to open switch 127, insulated rail section 110 and connections between said insulated rail section and relay such that the latter is energized when a train is present on insulated rail section 110.

24. In an automatic railway gate, and in combination with the gate proper thereof, a reversible motor for raising and lowering the gate, a pole-changing switch for reversing the motor comprising contacts 53 and 54 and a movable member for connecting said contacts respectively with the motor to operate it in opposite directions, a source of current, a connection from contact 53 to said source of current comprising normally closed switch 127, and a normally open switch 123, relay 104 adapted to close switch 123, insulated rail section 109, connections between said insulated rail section and relay 104 such that a train on said rail section energizes relay 104, relay 106 controlling switch 127, insulated rail section 110, battery 115 and connections between said insulated rail section, relay and battery such that the relay is energized when a train is present on the insulated rail section to open switch 127, a second circuit including a battery and a switch 107 controlled by relay 104 and including a coil of relay 106 for maintaining the armature of relay 106 in closed position after it has been attracted by the relay.

25. In an automatic railway gate, and in combination with the gate proper thereof, a reversible motor for raising and lowering the gate, a pole-changing switch for reversing the motor comprising contacts 53 and 54 and a movable member for connecting said contacts respectively with the motor to operate it in opposite directions, a source of current, a connection from contact 53 to said source of current comprising normally closed switch 127 and normally open switches 123 and 227 arranged parallel to each other and respectively in series with the normally closed switch 127, relay 104 adapted to close switch 123, insulated rail section 109, connections between said insulated rail section and relay 104 such that a train on said rail section energizes relay 104, relay 105 adapted to close switch 227, insulated rail section 111 and connections therefrom to relay 105 such that a train on said rail section energizes relay 105, relay 106, a circuit including insulated rail section 110 and the coil of relay 106 adapted to be closed by a train on section 110 to energize said relay to attract its armature and open switch 127, and a second circuit adapted to energize relay 106 to maintain its armature in closed position comprising switch 107 controlled by relay 104, switch 172 controlled by relay 105 and switch 176 controlled by relay 106.

26. In an automatic railway gate, and in combination with the gate proper there-

of, a reversible motor for raising and lowering the gate, a pole-changing switch for reversing the motor comprising contacts 53 and 54 and a movable member for connecting said contacts respectively with the motor to operate it in opposite directions, a source of current, a connection from contact 53 to said source of current comprising normally closed switch 127 and normally open switches 123 and 227 arranged parallel to each other and respectively in series with the normally closed switch 127, relay 104 adapted to close switch 123, insulated rail section 109, connections between said insulated rail section and relay 104 such that a train on said rail section energizes relay 104, relay 105 adapted to close switch 227, insulated rail section 111 and connections therefrom to relay 105 such that a train on said rail section energizes relay 105, relay 106, a circuit including insulated rail section 110 and the coil of relay 106 adapted to be closed by the presence of traffic on section 110 to energize said relay to attract its armature and open switch 127, and a second circuit adapted to energize relay 106 to maintain its armature in closed position comprising switch 107 controlled by relay 104, switch 172 controlled by relay 105 and switch 176 controlled by relay 106.

27. In an automatic railway gate and in combination with the gate proper thereof, a reversible motor for raising and lowering the gate, a pole-changing switch for reversing the motor comprising contacts 53 and 54 and a movable member for connecting said contacts respectively with the motor to operate it in opposite directions, a source of current, a connection from contact 53 to said source comprising normally open switches 123 and 227 arranged in parallel, relay 104 adapted to close switch 123 when energized by a train upon the rails at a distance from the gate, relay 105 adapted to close switch 227 when energized by a train on the rails at a distance from the gate, a connection from contact 54 to the source of current comprising switches 123 and 160 and closed by said switches when unaffected by the relays 104 and 105.

28. In an automatic railway gate and in combination with the gate proper thereof, a reversible motor for raising and lowering the gate, a pole-changing switch for reversing the motor comprising contacts 53 and 54, and a movable member for connecting said contacts respectively with the motor to operate it in opposite directions, a source of current, a connection from contact 53 to the source of current including a switch 123, a relay 104 controlling said switch, a pair of rails divided and insulated adjacent the gate, a pair of interlocking relays connected respectively across the rails at opposite sides of the insulation, a pair of batteries likewise 123

connected across the rails respectively at opposite sides of the insulation, and each maintaining the interlocking relay upon the same side of the insulation normally energized, a pair of switches controlled by each interlocking relay, one of which is normally maintained closed and the other normally maintained open by the relay, the normally open switch of one relay being connected to 6 the normally closed switch of the other relay, and each connected pair of switches being interposed in parallel to the other pair of connected switches in a circuit including a coil of relay 104, whereby when

either of said interlocking relays is deenergized by a train upon the rails, it locks out the other interlocking relay and energizes relay 104 to lower the gate, and a normally closed connection from contact 51 to the source of current for supplying a current 15 through the motor to operate the same to raise the gate when the movable member of the pole-changing switch is in engagement with said contact 54.
